LASTING MACHINE

Albin C. Eek, Webster Groves, Mo., assignor to
 United Shoe Machinery Corporation, Flemington, N. J., a corporation of New Jersey

Application March 20, 1946, Serial No. 655,754

8 Claims. (Cl. 12—4)

1

This invention relates to lasting machines, and more particularly to machines for lasting the heel ends of shoes. An object of the invention is to provide a heel-end-lasting machine such as disclosed in United States Letters Patent No. 1,852,015, granted on April 5, 1932, on an application of J. C. Jorgensen's with means for slitting the margin of the upper at the front end of the heel seat in operating on stitchdown shoes of that kind in which the margin of the upper is turned inward at the heel end and outward forwardly of the heel end, and the invention is accordingly herein shown as applied to a machine of that character. It is to be understood, however, that the invention is not limited in its applicability to machines constructed precisely in accordance with that disclosure.

The machine shown in the above-mentioned Letters Patent is provided with a pair of wipers movable to wipe the marginal portion of the heel end of an upper inwardly over an insole on a last, members movable with the wipers in fixed relation thereto from which to drive fastenings to fasten the upper, and driver blocks movable with these members and the wipers and each provided with a plurality of drivers for driving corresponding fastenings upon operative movements of the blocks heightwise of the shoe. For purposes of this invention, the construction herein shown includes knife carriers movable with the above-mentioned members in the wiping operation and guided by them independently of the driver blocks for operative movements heightwise of the shoe, knives supported by the carriers for slitting the margin of the upper over the insole in response to the operative movements of the carriers, and spring means for thus operating the carriers yieldingly by the operative movements of the driver blocks. More particularly, as herein illustrated, the knife carriers have portions thereof extended lengthwise of the shoe to positions underlying portions of the driver blocks, and the driver blocks are provided with spring-pressed plungers arranged to engage the extended portions of the carriers to operate the carriers. To adapt the upper-slitting means, moreover, for use on shoes of different sizes, the knives are mounted on knife holders which are adjustable lengthwise of the shoe relatively to the carriers.

The novel features of the invention will now be more particularly described with reference to the accompanying drawings and thereafter pointed out in the claims.

In the drawings,

Fig. 1 is a view partly in front elevation and

2

partly in section of a portion of a machine such as shown in the above-mentioned Letters Patent with the present invention applied thereto, the parts being shown in the positions which they occupy when the wipers are at the limits of their inward wiping movements but prior to the driving of the fastenings;

Fig. 2 is mainly a plan view of one of the wipers and of parts associated therewith;

10 Fig. 3 is a view showing in right-hand side elevation the portion of the structure at the left-hand side of the line III—III in Fig. 1, with parts broken away;

Fig. 4 is a section on the line IV—IV of Fig. 3;

15 Fig. 5 is a section on the line V—V of Fig. 4; and

Fig. 6 is a perspective view of a shoe as it appears after the operation of the machine thereon.

The shoe shown in Fig. 6 is a stitchdown shoe 20 of that kind in which the upper materials are lasted inwardly over an insole *a* on the last at the heel end and the margin of the outer layer *b* of the upper materials is turned outward forwardly of the heel end. Included in the upper materials is a lining *c* the margin of which is customarily lasted inwardly over the insole and secured to the insole by cement all around the shoe prior to the lasting of any other portion of the upper materials. Between the lining and the outer layer *b* at the heel end of the shoe is a counter *d*. After the lasting of the lining the shoe may be conveniently presented to a machine such as shown in the above-mentioned Letters Patent for lasting the margin of the heel-end 25 portion of the outer layer inwardly over the insole and for securing it, together with the flange of the counter *d*, to the insole by driving a plurality of tacks *t*. The machine includes a shoe support or jack 2 provided with a last pin 4 which enters the usual spindle hole in the heel end of the last and by movement of which the shoe is presented bottom upward to the lasting instrumentalities. In the operation of the machine the upper materials are clamped about the heel end of the last 30 by a heel band 6, after which the still unlasted margin of the heel end of the upper is wiped inwardly over the insole by a pair of wipers 8 which are advanced bodily lengthwise of the shoe and are closed inwardly widthwise of the shoe. It will be understood that in operating on a shoe of the kind herein shown it is the margin of the outer layer *b* of the upper materials which is thus wiped inwardly, together with the margin of the counter *d* if an unmolded counter is used.

Secured respectively to the different wipers to

move therewith, as disclosed in the previously mentioned Letters Patent, are members 10 which may be termed tacker blocks, each of these members being provided with a plurality of passages (not herein shown) from which tacks are driven through the wipers to fasten the upper. Movable with the tacker blocks and the wipers are driver blocks 12 each provided with a plurality of tack drivers 14 for driving the tacks, the driver blocks 10 being movable downwardly in guideways 16 in the tacker blocks to operate the drivers. Such downward movements are imparted to the driver blocks by spring-operated means not herein shown but fully disclosed in the above-mentioned Letters Patent, such means being connected to upstanding headed projections 18 on the driver blocks.

For purposes of this invention there is secured by screws 20 to the front-end portion of each of the tacker blocks 10 a bracket 22 which, in cooperation with the front face of the tacker block, provides a guideway 24 for a vertically movable knife carrier 26. At its lower end the knife carrier has a horizontally extending portion 28 provided with a T-shaped guideway 30 on which is mounted a knife holder 32. Secured to this knife holder by a bolt 34 and a nut 36 is a knife 38 which in response to downward movement of the knife carrier 26 slits the margin of the outer layer b of the upper materials at the front end of the heel seat. As shown particularly in Fig. 5, a portion of the knife 38 fits into a recess in the holder 32 to prevent any turning of the knife about the bolt 34, and formed also in the knife is a vertical slot 40 (Fig. 4) through which the bolt extends, this slot permitting vertical adjustment of the knife with respect to the holder. The lower face 42 (Fig. 3) of the holder is arranged to engage the margin of the upper forwardly of the heel seat to limit the depth of the cut of the knife.

Threaded in the upper end of each knife carrier 26 is a vertical rod 44 having a nut 46 threaded on its upper end, and between this nut and a washer 48 engaging the upper end of the bracket 22 and of the tacker block 10 is a spring 50. This spring holds the knife carrier initially at the limit of its upward movement determined by engagement of its horizontal portion 28 with the lower end of the bracket 22 and returns the carrier to that position after its downward movement. The horizontal portion of the knife carrier is extended rearwardly to a position underlying the front-end portion of the driver block 12, the lower portion of the tacker block 10 as used heretofore being cut back to permit this arrangement, as is also a portion of the underlying wiper 8. Arranged to engage the top of this rearwardly extending portion of the knife carrier is the lower end of a plunger 52 mounted in a recess in the driver block 12 and provided at its upper end with a rod 54 extending upwardly through a partition 56 in the driver block into another recess in the block above the partition. Between the partition 56 and an enlarged head on the lower end of the plunger 52 is a spring 58. Threaded on the rod 54 above the partition 56 is a nut 60, and between this nut and a screw 62 threaded in the driver block is another spring 64. It will be evident that the tendency of both springs 58 and 64 is to move the plunger 52 downward relatively to the driver block 12 as far as permitted by engagement of the nut 60 with the partition 56, and when downward movement is imparted to the driver block to operate the tack

drivers 14, the block acts through the two springs and the plunger 52 to impart downward movement also to the knife carrier 26 against the resistance of the spring 50 and thus to cause the knife 38 to slit the upper. When the downward movement of the knife carrier is stopped by engagement of the lower face 42 of the knife holder 32 with the margin of the upper, the springs 58 and 64 may yield to permit continued movement of the driver block until the tacks are fully driven. The two springs 58 and 64, both of which perform the same function, are provided because of the inconvenience of providing in the driver block a single spring of sufficient strength through which to operate the knife carrier.

Secured on the top of the front end portion of the horizontal extension 28 of each knife carrier 26 is an L-shaped bracket 66 in which is rotatably mounted a screw 68 held against lengthwise movement by engagement of the bracket with a knob 70 and a flange 72 on the screw. The screw is threaded in the knife holder 32 and extends through the previously mentioned slot 40 in the knife 38. It will therefore be evident that by the two screws 68 the knife holders 32 may be adjusted each independently of the other along the guideways 30 to vary as desired the locations of the slits in the margin of the upper in operating on shoes of different sizes.

Having described the invention, what I claim as new and desire to secure by Letters Patent of the United States is:

1. In a lasting machine, a pair of wipers movable to wipe the marginal portion of the heel end of an upper inwardly over an insole on a last, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being further movable relatively to said members heightwise of the shoe thus to operate the drivers, knife carriers supported by said members also to move with them and the wipers, said knife carriers being guided independently of the driver blocks for movements heightwise of the shoe but being thus movable by the driver blocks, and knives supported by said carriers for slitting the margin of the upper over the insole in response to such movements of the carriers heightwise of the shoe.

2. In a lasting machine, a pair of wipers movable to wipe the marginal portion of the heel end of an upper inwardly over an insole on a last, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being further movable relatively to said members heightwise of the shoe thus to operate the drivers, knife carriers also movable with said members and the wipers, said knife carriers being supported independently of the driver blocks for movements heightwise of the shoe, knives supported by said carriers for slitting the margin of the upper over the insole in response to such movements of the carriers heightwise of the shoe, and spring means for transmitting force yieldingly from the driver blocks to said carriers thus to operate the carriers.

3. In a lasting machine, a pair of wipers movable to wipe the marginal portion of the heel end of an upper inwardly over an insole on a last, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being further movable relatively to said members heightwise of the shoe thus to operate the drivers, knife carriers also movable with said members and the wipers, said knife carriers being guided by said members independently of the driver blocks for movements heightwise of the shoe, knives supported by said carriers for slitting the margin of the upper over the insole in response to such movements of the carriers heightwise of the shoe, springs in said driver blocks for operating the knife carriers yieldingly by the movements of the driver blocks, and other springs for returning the knife carriers when the driver blocks are returned.

4. In a lasting machine, a pair of wipers movable to wipe the marginal portion of the heel end of an upper inwardly over an insole on a last positioned bottom upward, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being also downwardly movable relatively to said members to operate the drivers, knife carriers movable with said members and the wipers, said knife carriers being guided by said members independently of the driver blocks for downward and upward movements and having portions thereof extended lengthwise of the shoe to positions underlying portions of the driver blocks, knives supported by said carriers for slitting the margin of the upper over the insole in response to downward movements of the carriers, and spring means arranged to apply pressure to said extended portions of the carriers to operate the carriers in response to the downward movements of the driver blocks.

5. In a lasting machine, a pair of wipers movable to wipe the marginal portion of the heel end of an upper inwardly over an insole on a last, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being further movable relatively to said members heightwise of the shoe thus to operate the drivers, knife carriers supported by said members also to move with them and the wipers, said knife carriers being guided independently of the driver blocks for movements heightwise of the shoe, knives supported by said carriers for slitting the margin of the upper over the insole in response to such movements of the carriers heightwise of the shoe, the carriers having thereon means for engaging the shoe to limit their movements, and springs for transmitting force from the driver blocks to the carriers to operate the carriers, said springs being yieldable to permit further movements of the driver blocks when the carriers are stopped by the shoe.

5 6. In a lasting machine, a pair of wipers movable to wipe the marginal portion of the heel end of an upper inwardly over an insole on a last, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being further movable relatively to said members heightwise of the shoe thus to operate the drivers, knife carriers also movable with said members and the wipers, said knife carriers being supported independently of the driver blocks for movements heightwise of the shoe but being thus movable by the driver blocks, and knives supported by said carriers for slitting the margin of the upper over the insole in response to such movements of the carriers heightwise of the shoe, said knives being adjustable each independently of the other in directions lengthwise of the shoe.

25 7. In a lasting machine, a pair of wipers movable to wipe the marginal portion of the heel end of an upper inwardly over an insole on a last, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being further movable relatively to said members heightwise of the shoe thus to operate the drivers, knife carriers also movable with said members and the wipers, said knife carriers being guided independently of the driver blocks for movements heightwise of the shoe but being thus movable by the driver blocks, knife holders on said carriers, knives on said holders for slitting the margin of the upper over the insole in response to the movements of the carriers heightwise of the shoe, and means for adjusting said knife holders relatively to the carriers in directions lengthwise of the shoe.

30 8. In a lasting machine, a pair of wipers movable to wipe the marginal portion of the heel end of an upper inwardly over an insole on a last positioned bottom upward, members from which to drive fastenings to fasten the upper, said members being mounted to move respectively with the different wipers in fixed relation thereto in the wiping operation, driver blocks mounted to move respectively with said members and each provided with a plurality of drivers for driving corresponding fastenings, the driver blocks being also downwardly movable relatively to said members to operate the drivers, knife carriers movable with said members and the wipers, said knife carriers having portions guided by said members independently of the driver blocks for downward and upward movements and other portions extended horizontally lengthwise of the shoe to positions underlying portions of the driver blocks, knife 35 holders guided by said horizontal portions of the knife carriers for adjusting movements lengthwise of the shoe and having thereon knives for slitting the margin of the upper over the insole in response to downward movements of the carriers, and spring means in the driver blocks arranged to act on said extended portions of the carriers to operate the carriers yieldingly in response to the downward movements of the driver blocks.
